[57] CLAIM

The ornamental design for a door panel, as shown and described.

DESCRIPTION

FIG. 1 is a front elevational view of a door panel showing a first embodiment of my new design, the rear elevational view being identical to the front;

FIG. 2 is a front elevational view of a second embodiment of my new design, the rear elevational view being identical to the front;

FIG. 3 is a cross-sectional view taken along line 3—3 of FIG. 1;

FIG. 4 is a cross-sectional view taken along line 4—4 of FIG. 1;

FIG. 5 is a cross-sectional view taken along line 5—5 of FIG. 1;

FIG. 6 is a cross-sectional view taken along line 6—6 of FIG. 1;

FIG. 7 is a cross-sectional view taken along line 7—7 of FIG. 2; and

FIG. 8 is a cross-sectional view taken along line 8—8 of FIG. 2.

The broken line showing of a door is for illustrative purposes only and forms no part of the claimed design.
